UNITED STATES PATENT OFFICE.

LUDY W. WOOLWINE, OF BECKWITH, WEST VIRGINIA, ASSIGNOR OF ONE-HALF TO
DANIEL BOONE, OF ABEY, WEST VIRGINIA.

SAFETY-CRANK.

1,295,408.

Specification of Letters Patent. Patented Feb. 25, 1919.

Application filed August 3, 1917. Serial No. 184,276.

To all whom it may concern:

Be it known that I, LUDY W. WOOLWINE, a citizen of the United States, residing at Beckwith, in the county of Fayette and State of West Virginia, have invented a new and useful Safety-Crank, of which the following is a specification.

The present invention appertains to a safety crank for starting automobiles or other internal combustion engines, and is particularly an improvement over the safety cranking device disclosed in my Patent No. 1,168,694, granted January 18, 1916.

It is the object of the invention to provide novel and improved means for automatically disconnecting the hand crank from its shaft in the event that the shaft has a reversed rotation, as in case of back firing, whereby to prevent injury to the person cranking, as is not infrequently the case with the use of ordinary rigid cranks.

The invention has for a more specific object, provision of simple yet effective means for releasing the main pawl or dog of the crank arm from the ratchet wheel of the shaft, controlled by the handle of the crank.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

The invention is illustrated in the accompanying drawing, wherein:

Figure 1 is a side elevation of the improved crank, portions being broken away and shown in section.

Fig. 2 is a section on the line 2—2 of Fig. 1, portions being broken away.

The crank is used, as usual, for rotating the engine starting shaft 1 having a clutch head 2 for engaging the engine shaft to turn it over, and said crank embodies the radial crank arm 3 provided at its inner end with a bifurcated portion or fork 4 mounted loosely or rotatably upon the shaft 1, a ratchet wheel 5 being secured upon the shaft within said fork to rotate with the shaft.

A U-shaped cover 6 is preferably secured, by means of screws or otherwise, upon the

fork 4 to inclose the slot thereof and the ratchet wheel 5, to avoid the collection of dirt or grit therein. A rod or stem 7 is 60 slidable through a longitudinal bore 8 with which the arm 3 is provided, said bore extending from the slot of the fork to a recess 9 with which the outer free end of the arm is provided, and the inner end of the rod 7 has a pawl or dog 10 engageable with the teeth of the ratchet wheel 5. Thus, when 65 the dog 10 engages the ratchet wheel, the crank can be rotated counter clockwise, as seen in Fig. 2, for rotating the shaft 1 to start the engine. The foregoing parts, with the exception of the cover 6, are disclosed 70 in said patent, and the gist of the present invention resides in the novel means for retracting the rod 7 and dog 10, controlled from the crank handle 11 of the crank, as will presently appear.

The handle 11 has a bore extending from its inner end and is fitted rotatably upon a tubular spindle 12 having one end secured in any suitable manner to the arm 3 adjacent to its outer free end. A shaft 13 is 80 journaled for rotation through the spindle 12 and has one end threadedly or otherwise engaged to the handle 11 whereby said shaft and handle rotate together, the shaft holding the handle upon the spindle. The other 85 end of the shaft 13 has a ratchet wheel 14 thereon abutting the corresponding end of the spindle 12, to hold the shaft in place.

A rocking block or member 15 is disposed within the recess 9, and is provided with a 90 circular recess 16 fitting a circular head 17 with which the outer end of the rod is provided, whereby to provide a pivotal connection between said rod and member, a screw 18 or other retaining element being engaged 95 with the rod 7 and holding in place a washer 19 which overlaps the member 15 to hold it assembled with the rod and against the wall of the recess 9. The member 15 has an outwardly projecting dog or pawl 20 provided with a series of ratchet teeth 21 engageable with the teeth of the ratchet wheel 14. A coiled wire retractile spring 22 disposed at one side of the member 15, has one 100 end connected thereto and its other end connected to the arm 3, whereby said spring tends not only to swing the member 15 toward the left, as seen in Fig. 2, but also tends to move the member 15 and rod 7 105 toward the shaft 1 to engage the dog 10 110

with the ratchet wheel 5. A cover 23 is secured to the outer portion of the arm over the recess 9, to inclose the parts therein, and protect them from dirt and grit.

5 In operation, when the handle 11 is revolved to turn the crank counter clockwise, as seen in Fig. 2, the handle will be rotated clockwise, with respect to the crank arm, opposite to the arrow in Fig. 2, and the teeth 10 of the ratchet wheel can snap past the teeth 21, the spring 22 pulling the member 15 inwardly, to hold the dog 10 against the ratchet wheel 5, whereby the shaft 1 will turn with the crank. Should the engine 15 back fire, thereby turning the shaft 1 and ratchet wheel 5 clockwise in the direction of the arrow in Fig. 2, this will carry the dog 10, rod 7 and arm 3 but a very short distance with the shaft 1 clockwise, as seen in Fig. 2. 20 This is due to the fact that the handle 11 being gripped by the operator and being moved clockwise, will cause the ratchet wheel 14 to rotate counter clockwise, with respect to the crank arm 3, as indicated by 25 the arrow in Fig. 2, and teeth of the ratchet wheel 14 will, therefore, engage the teeth 21 and pull the dog or rack member 20 outwardly against the tension of the spring 22, thereby retracting the rod 7 and dog 10. 30 This will remove the dog 10 from the ratchet wheel 5, after the arm 3 has moved but a short distance, thus disengaging the crank from the shaft, so that the crank will not be turned farther with the shaft 1, which will 35 avoid injury to the operator. It will be noted that the dog 20 having the teeth 21 will provide a rack engageable with the ratchet wheel during its rotation in one direction, to retract the dog 10 in case of the

reversed rotation of the crank arm and handle. However, as soon as the crank is again turned counter clockwise, as seen in Fig. 2, the rotation of the handle 11 clockwise relatively to the arm, will enable the dog 10 to again engage the ratchet wheel 5 to rotate the shaft 1, no resetting being necessary after the engine has back fired, since the dog 10 after being automatically retracted from the ratchet wheel 5, will again engage it as soon as the arm is rotated in the proper direction for starting the engine.

Having thus described the invention, what is claimed as new is:

A safety crank embodying a shaft, a crank arm rotatable thereon, gripping means rigid 55 on the shaft, a handle rotatably mounted on the arm, gripping means rigid on the handle, slidably mounted engaging means associated with the arm and in removable engagement with the gripping means on the shaft, said means comprising a rod, a rack pivotally secured to the rod with its teeth normally in engagement with the gripping means on the handle, and an element secured to the arm and to the rack to retain the rack in movable 60 engagement with the gripping means on the handle and actuatable by the reverse movement of the handle due to back-firing of the engine to release the slidably engaging means from the gripping means on the 65 shaft.

In testimony that I claim the foregoing as my own, I have hereto affixed my signature in the presence of two witnesses.

LUDY W. WOOLWINE.
